UNITED STATES PATENT OFFICE

2,381,298

STEAM PUMP

Paul A. McCormick, San Diego, Calif.

Application December 21, 1943, Serial No. 515,169

1 Claim. (Cl. 103—16)

The present invention relates generally to new and useful improvements in steam pumps, and has for its primary object to provide a power plant of this type comprising a unique combination and arrangement for transmitting power to any suitable point through the medium of a suitable fluid.

Another very important object of the invention is to provide an apparatus of the aforementioned character which embodies novel means for automatically controlling or regulating the power which is transmitted therefrom.

Other objects of the invention are to provide a power plant of the character described which will be comparatively simple in construction, strong, durable, highly efficient and reliable in use and operation, compact, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of the invention.

Figure 2 is a longitudinal sectional view, taken substantially on the line 2—2 of Figure 1.

Figure 3 is a fragmentary view in cross section, taken substantially on the line 3—3 of Figure 1.

Figure 4 is a fragmentary view in cross section, taken substantially on the line 4—4 of Figure 1.

Figure 5 is a plan view of the regulating cylinders.

Figure 6 is a detail view in cross section, taken substantially on the line 6—6 of Figure 2.

Figure 7 is a fragmentary view in longitudinal section, taken substantially on the line 7—7 of Figure 1.

Figure 8 is a detail view in side elevation of one of the valve operating links.

Referring now to the drawings in detail, it will be seen that the embodiment of the invention which has been illustrated comprises a base 1 of suitable dimensions and material. The base 1 includes a raised or elevated forward end portion 2. Suitable supports 3 are provided beneath the base 1. Guides 4 rise from the sides of the base 1.

Mounted on the rear end portion of the base 1 is a steam engine 5. The engine 5 comprises a horizontal cylinder 6 through the forward end of which a slidable rod 7 extends. A piston 8 is

mounted on the rod 7 for reciprocation in the cylinder 6. A valve 9 of the sliding box type is provided for the cylinder 6. A line 10 connects the valve 9 to a steam boiler.

Projecting forwardly from the upper portion of the cylinder 6 is a bracket 11. A lever 12 is pivotally mounted, at an intermediate point, for vertical swinging movement on the bracket 11. The upper end portion of the lever 12 is operatively connected to the rod 13 for actuating the valve 9. The lower end portion of the lever 12 is engageable by spaced pins 14 on the piston rod 7 for actuation by said piston rod.

Mounted longitudinally on the forward end portion 2 of the base 1 is a series of fluid pumps 15. The pumps 15 include cylinders 16 having mounted therein reciprocating pistons 17. The rods 18 of the pistons 17 are connected to a transverse line shaft 19 on the forward end portion of the piston rod 7. Guide shoes 20 on the end portions of the shaft 19 are slidable on the base 1 between the side members 4.

Control valves 21 of the slideable box type are provided for the cylinders 16 of the pumps 15. The rods 22 of the valves 21 are connected to a transverse line shaft 23 which, in turn, is connected by a rod 24 to the lever 12 for actuation thereby.

The outlets 25 of the valves 21 are connected to multi-way valves 26. A fluid pressure line 27, to any suitable point at which the power is to be used, is connected to the valves 26 by means including a manifold 28 and branches 29. A fluid return line 30 is connected to the intakes of the valves 21 through the medium of a manifold 31 and branches 32. Branches 33 also connect the manifold 31 to the valves 26. A manually adjustable back pressure regulating valve 34 is interposed in the fluid return line 30.

Mounted beneath the base 1 are pairs of opposed cylinders 35 and 36, the former being smaller than the latter and, further, being of different sizes, as illustrated to advantage in Figure 5 of the drawings. The pressure line 27 is also connected to the cylinders 35, as at 37. Lines 38 connect the cylinders 36 to the steam boiler. Pistons 39 and 40 in the cylinders 35 and 36, respectively, are connected by a rod 41.

Brackets 42 are mounted on the valves 26. Pivotally mounted on the brackets 42 are bell crank levers 43. Links 44 connect the bell crank levers 43 to the piston rods 41 for actuating the valves 26. Pin and slot connections 45 permit limited movement of the pistons 39 and 40 independently of the valves 26.

Also mounted on the bracket 11 is a water injector 46 which is operatively connected at 47 to the lever 12. An intake line 48 from a suitable source of water supply is connected to the injector 46. A line 49 connects the injector 46 to the boiler. A valve controlled bypass line 50 is connected to the water line 49 to the boiler.

Briefly, the operation of the apparatus is as follows:

Steam from the boiler actuates the engine 5 in the usual manner. The engine 5, in turn, actuates the fluid pumps 15 through the rod 7, the shaft 19, the rods 18, et cetera. The lever 12 is periodically actuated by the pins 14 on the rod 1 for operating the valve 9 and the water injector 46. With the valves 26 in the position shown in Figure 2 of the drawings, the line 27 is in communication with the outlets of the pumps 15 and fluid under pressure is delivered to the desired point, such, for example, as one or more rotary 20 motors or turbines. This fluid returns to the cylinders 16 of the pumps 15 through the line 30. Fluid pressure from the line 27 urges the pistons 39 rearwardly in the cylinders 35, which movement is resisted at all times by the full pressure of steam from the boiler in the cylinders 36 acting on the pistons 40. However, when a predetermined pressure in the line 27 is passed, the pistons 39 are actuated thereby until arrested by engagement of the pistons 40 with the closed rear ends 25 of the cylinders 36. In this manner, the valves 26 are actuated for disconnecting the pressure line 27 from the outlets of the pumps 15 and for connecting the return line 30 to said outlets through the manifold 31 and the branches 33. When this occurs, the pumps 15 are cut out of the fluid circuit. The different sizes of the cylinders 35 and the pistons 39 therein governs the order in which the pumps 15 are cut out. That is, the cylinders 35, from the largest to the smallest thereof, successively cut out the respective pumps connected thereto. From the foregoing it will be seen that the load on the steam engine 5 is automatically regulated to meet various conditions. The links 44 are operable in slots 51 which are provided therefor in the base 1.

Ordinarily, there would be a slight sag or lowering of pressure in the line 27 each time the pistons 17 in the cylinders 16 reached the ends of their strokes. However, this is prevented, or sub-

stantially prevented, by the steam from the boiler moving the pistons 39 forwardly in their cylinders 35 through the medium of the pistons 40 and the rods 41. The pin and slot connections 45 permit pulsation of the mechanism without actuating the valves 26. The valve 34 functions as a brake. By closing this valve 34, back pressure is created against the rotary motor or other device which is being driven.

It is believed that the many advantages of an apparatus constructed in accordance with the present invention will be readily understood, and although a preferred embodiment is as illustrated and described, it is to be understood that changes in the details of construction and in the combination and arrangement of parts may be resorted to which will fall within the scope of the invention as claimed.

What is claimed is:

An apparatus of the character described comprising a supporting structure, a steam engine mounted on the supporting structure and adapted for connection with a steam boiler, a fluid pump mounted on the supporting structure and having an inlet and an outlet, said steam engine and said pump having pistons operatively connected with each other for simultaneous movement, a multi-way valve having a main casing communicating with the outlet of the pump and an auxiliary casing communicating with its main casing, a fluid pressure line communicating with the auxiliary casing of said valve, a fluid return line communicating with the auxiliary casing of the valve and with the inlet of the pump, a valve member 30 35 40 45 50 55 60 65 70 75 80 85 90 95 100 105 110 115 120 125 130 135 140 145 150
